PROCESS FOR PYROLYSIS OF LIQUID HYDROCARBONS

Joseph F. Donnelly, Lemont, Ill.

Application March 30, 1934, Serial No. 718,181

13 Claims.

(Cl. 196—48)

My invention relates to a process for the pyrolysis of hydrocarbons and particularly to the heat treatment of petroleum hydrocarbons of complex character, whereby such hydrocarbons are converted into lighter hydrocarbons and residual products of solid character. More particularly, my invention relates to a process whereby heavy hydrocarbon oils are converted into lighter hydrocarbon oils, together with the formation of coke through the pyrogenic treatment of hydrocarbon oils.

An object of my invention is to produce commercial products which may be exemplified by the production of liquid hydrocarbons, such as gasoline, Diesel engine distillate fuel, furnace oil, gas oil, lubricating oil distillate, etc., and heavier residual products such as fuel oil, together with solid end products such as coke.

Another object of my invention is the production of coke by progressive building up of separated coke masses by progressive pyrogenic decomposition of heavy hydrocarbon oils deposited upon the surfaces of the maintained separated masses.

Another object of my invention is to produce relatively uniform bodies of coke in an automatic and progressive manner. A further object of my invention is to treat coals so as to recover the volatile constituents thereof.

I have devised a novel form of apparatus for carrying out my process and illustrate the preferred form thereof in the drawings, in which Figure 1 is a processing flow diagram and shows one method of applying the present invention in conjunction with a petroleum refining process.

Figure 2 is a side elevation partly in section of a preferred apparatus for carrying out the invention.

Figure 3 is an end elevation partly in section of the apparatus shown in Figure 2.

Figure 4 is an end elevation partly in section of a modified form of the apparatus shown in Figure 3.

In carrying out my process with the preferred form of apparatus herein shown, crude oil or its derivatives, such as topped crude, gas oil; or oil derived from coal, shale, wood, vegetable or animal, etc., is supplied by pump 1, from any suitable source to heat exchangers 2 and 3 where it is indirectly heated by the hot vapors passing through said heat exchangers. The preheated charge oil is then mixed with the effluent from a highly heated cracking or distilling coil 52, as controlled by the adjacent valve 4, the mixture being then passed into high pressure vapor separator 5,

wherein separation of high boiling and low boiling fractions is effected, the desired separation being controlled by supplying relatively cold oil, preferably crude gasoline, naphtha or kerosene, into the top of said separator through trim line 6, supplied from any suitable source. I prefer to herein separate out as liquid all fractions having boiling points over approximately 650° F. The fractions having boiling points under 650° F. remaining as vapor are then passed through coil 7, in furnace 8, where they are heated to a temperature sufficient to effect carbonization of decomposable oil, being applied to the agitated carbon bed 9, contained in semi-circular shell 9' of the carbonizer 10. For illustration the products leaving coil 7, will range from 800° F. to 1200° F., or higher, depending on the amount of heat to be transmitted thereby to the carbonizer 10. The vapor or gases in coil 7 may therein be subjected to any desired degree of molecular alteration.

Semi-circular plate 9' is initially charged with carbonaceous solid particles, such as coke, coal, charcoal or the like, or with metallic masses of suitable size and shape, to provide a bed of suitable volume, preferably sufficient to adsorb the decomposable liquid supplied thereto for decomposition.

The bed 9 is preferably heated sufficiently to effect decomposition and carbonization as herein-after described, before supplying decomposable oil thereto.

It is to be understood that the specific temperatures and pressures etc., herein given are for illustrative purposes, and are intended only as examples to promote a better understanding of the teaching of the invention, and may be employed within wider or narrower limits than shown without departing from the fundamentals of the process.

Pressure on the vapor separator may be controlled by regulating valves 11, 12 and 13, or 14, and closing valves 15 and 16. If desired, I may mix fixed gas such as natural or cracking still gas, or light hydrocarbons, such as crude gasoline, naphtha, etc., either as liquid or vapor, with the vapors entering heating coil 7, which may therein be subjected to any desired degree of molecular alteration, same being supplied from any convenient source by pump or compressor 17 through valve 18. The highly heated gas and vapor is passed by perforated pipes 19, controlled by valves 14 through bed 9, to which it imparts heat and partial pressure effect sufficient to effect rapid carbonization of the oil coating the surface of the particles composing the said bed.

The liquid remaining in the vapor separator 5, is delivered by pump 20, to coil 21, where it is heated under pressure controlled by valve 22, to a temperature sufficient to effect vaporization in vaporizer 23, of substantially all fractions having boiling point lower than that necessary to produce petroleum asphalt, the object being to effect concentration of the highly complex hydrocarbons in the liquid residuum. The hot concentrated residuum is delivered through valve 24, to pump 25, from which it is delivered under relatively high pressure to distributing header 26, controlled by valves 27, connected to distributor pipes 28, which are equipped with spray nozzles 29 for spraying the oil on the highly heated bed 9. If desired as an aid to the atomization and vaporization of volatile constituents of the oil being sprayed on the carbonizing bed, from any suitable source I may supply steam, gas, or light oil vapor 20 commingled therewith either at the point 29 or as shown through header 30 controlled by valves 31. If desired, I may heat the residuum above referred to in a furnace or other means before entering the carbonizer, in which case the residuum 25 will be heated to the maximum temperature without carbon fouling the heating means.

The vapors leaving the carbonizing element 10, pass through heat exchanger 3, thence between the jacket and shell of the carbonaceous solids 30 preheater 32, where it preheats the carbonaceous solid material which is subsequently treated in carbonizing element 10, or if desired the said vapor may be passed under reduced pressure directly to condenser 33, by opening valve 34, and 35 closing valves 35 and 37 and operating vacuum producing means 43', or the vapor leaving pre-heater 32, may be passed to condenser 33 as above, or to vaporizer 23, by manipulation of valves 34, 35, 37 and 38, in a manner well understood to those skilled in the art. Condensates from exchanger 3 are delivered by pump 39 to vaporizer 23, or may be delivered to the fresh oil line entering exchanger 2, depending on its characteristics, or it may be withdrawn from the system. The vapor leaving vaporizer 23, passes through exchanger 2, then to bubble tower 40, where the desired degree of fractionation is effected. The fractionated vapors are condensed in condenser 41 and the gases separated in gas separator 42. If desired elements 23, 40, 41, 42 and 46, may also be operated under reduced pressure by means 43'. From the foregoing, it will be seen that the vapor from the carbonizer 10 and from the vaporizer 23, may be fractionated and condensed separately and under different pressures, or may be commingled, fractionated and condensed together. Condensates separated in separator 43, are preferably delivered by pump 44, to bubble tower 40 for retreatment, 60 or may be withdrawn from the system through valve 44'. The temperature of the tower 40, is preferably controlled by trimming with condensates from separator 42, delivered thereto by pump 45. Products condensing in tower 40, are separated therein into two fractions of different boiling points, the lighter fraction thereof being withdrawn from the upper plates to a stripping tower 46, where it is stripped of its most volatile fractions which are returned as a vapor to the tower 40 through line 47. The condensate that accumulates in the bottom of the towers 40 and 46, constitutes selective differential boiling point stocks for reactive heat treatment in the system, or each may be withdrawn from the system 70 through cooler 48, by manipulation of valves 49, through

49', 50 and 50'. Distillate from separator 42, controlled by valve 50'', bubble tower 40, stripper 46, or from an extraneous source or mixtures thereof, is delivered by pump 51, to the inlet of coil 52, in furnace 53, where it is heated for sufficient time and to sufficient temperature to effect either distillation or cracking in any desired degree and amount within practical operating limits of the balance of the system, and with particular reference to the process of the invention, 10 the effluent of coil 52, being controlled by valve 53' and enters separator 5, mixed with preheated fresh charge oil as heretofore explained. While I have shown the present invention operating in conjunction with a coil type cracking operation it is to be understood, that the invention is not limited to or dependent on conjunctive operation with any particular type of distilling or cracking process, but may be operated successfully with several known cracking processes, or 20 if desired the process of the invention may be operated independently as a separate unit.

Adjustable equal-spaced mixing and separating blades 54, are attached to hollow cooled shaft 55, which rotates counter clockwise, the number of revolutions for a given time being regulated to prevent the carbonaceous masses from being consolidated into a solid and to remove therefrom carbonaceous particles that have attained the predetermined size, such particles being too large to pass between the blades will be carried thereby until an angle is reached where the particles will fall toward the shaft by gravity. The particles will then be intercepted by grid plate 56, attached to hollow cooled shaft 57, which will now be operated from shaft 55 or independently to elevate the plate 56, to permit the blades 54 to pass, and to discharge the carbon particles accumulated thereon, which particles will descend into the bottom of shell 10, where it will be conveyed to 40 cooler 60, by screw conveyor 58, having a hollow cooled shaft and which may be operated independently, valve 61 being open. Shaft 55, is driven through gear 59, by any suitable power means, not shown. During this operation super-heated steam may be passed into the bottom of drum 60 through valve 62, to prevent heavy oil vapors from entering and condensing therein. It being understood that drums 10 and 60, and all other parts of the apparatus are well insulated 50 where it is desired to prevent heat loss or condensation. During the accumulation of carbon in drum 60, valves 63, 64, 65 and 66 are closed.

When it is desired to empty the drum 60 of its accumulated carbon, conveyor 58 is stopped, additional steam is admitted through valve 62, to thoroughly purge the drum of any vapors that may be therein. When this is attained, as may be determined by withdrawing vapors from the top of the drum through a small water cooled 60 coil (not shown), attached thereto for the purpose, and testing the condensates thus obtained for oil. When the drum 60 is sufficiently purged of oil vapors to prevent danger of fire, then valve 64 is open to the atmosphere, or may be disposed of as desired. Valve 63 may now be slightly opened to admit a small quantity of cooling water through a spray device. The cooling is continued until the carbon has reached a temperature below its auto ignition point when exposed to the atmosphere. It is then removed from the bottom of the cooler and conveyed to storage by any suitable means not shown. It is to be understood that the carbon may be cooled in any suitable manner before or after removal. When the drum 70

is emptied it is again closed and steam is again admitted through valve 62 and out through valve 64, this operation being continued until all air is expelled from the drum. Any condensed water is withdrawn through drain valve 66, valve 64 is now closed and valve 61 is opened and conveyor 58 is again started. Drum 60 is also equipped with safety pressure valves not shown.

Fresh carbonaceous solid material to be treated is supplied from any suitable source to pre-heater 32, through supply means 67, valve 68, being closed. In the preferred method the pre-heater 32, is charged with small particles of coke, or coal, or other carbonaceous solid, and is therefore preheated to the maximum temperature obtainable from the vapors employed for preheating, this preheating may be done in any suitable manner. Air is purged from the preheater 32, by admitting superheated steam through valve 68, valve 70, being open, valve 71 and valve 72 being closed. Vapor or gas is purged from the preheater 32 by admitting superheated steam through valve 69, valves 70 and 72 being closed, valve 71 being open. When the preheater drum 25 is completely purged of all air, valves 69, 70 and 72 are closed, valves 68 are opened, and screw feed conveyor 73 is operated by any suitable motive means (not shown), to feed carbonaceous material in a regulated manner to the carbonizing bed 9 as required. Valve 71 is open and any volatile matter contained in the carbonaceous material vaporizable at the temperature prevailing in the preheater will be vaporized and removed from the preheater through valve 71. The finely divided preheated carbonaceous material fed to the carbonizing bed 9, will serve as nuclei for the progressive building up thereof into predetermined size particles by the carbonization on its surface of the complex constituents of the oil sprayed thereon through spray nozzles 29.

From the foregoing it will be seen that the concentrated substantially carbon saturated oil to be decomposed, in heated condition is sprayed in finely divided form, onto the material composing the carbonizing bed 9, and the highly heated vapors or gases from an extraneous source are passed through the bed thus imparting to the decomposable oil coating the surfaces and in the interstices of the particles composing the bed 50 sufficient heat and partial pressure effect to rapidly vaporize volatile constituents and effect carbonization of complex fractions contained in or sprayed on the bed 9. It will be obvious that the higher the temperature of the decomposable oil before contacting the carbonizing bed, and the higher the temperature of the vapor, gas, or steam passing through the bed, the more accelerated will be the rate of decomposition and carbonization of the material constituting the bed or being sprayed thereon. If the nature of the material to be decomposed and carbonized is such that it is impractical to preheat the same directly, I prefer to dilute such material before preheating, with a solvent of relatively low boiling temperature, then preheating the mixture to its maximum temperature without fouling the preheating element with carbon, then introducing the preheated mixture into the carbonizer. As a solvent or diluent, I prefer to use a liquid hydrocarbon that will substantially completely vaporize when released through the nozzles 29. By this method of carbonization of decomposable fluid there results a final carbon product having desirable characteristics such as a high degree of mass density, in contradistinction to porous

mass as results from present known methods of carbonization. Further, this method provides a continuous carbonizing process for the production of predetermined size particles, thus eliminating the expense incident to manufacturing briquettes from carbonaceous material. However, if it is desirable to produce very fine carbon particles, such as powder, it may be accomplished by this process. The operation will be the same as when making the larger size particles 10 with the apparatus heretofore described, except, the semi-circular carbon bed plate 9', will be slotted or perforated in the area beneath the carbon bed and between the pipes 19 to permit fine particles to fall through said plate. The plate 15 56, will be permanently elevated during this operation. The shaft 55 and blades 54, will be rotated at a speed to produce an attritional grinding effect of the particles constituting the bed 9, resulting in physical disintegration of generated 20 carbon, the operation being conducted so that the rate of carbonization, and of carbon physical disintegration are synchronized so that they are substantially equal.

When making very fine carbon particles I may 25 replace the carbonaceous material of bed 9, with metal particles of suitable size, preferably spherical in shape, to produce a carbonizing surface, the blades 54 and shaft 55, being rotated at sufficient speed to cause physical disintegration 30 of the carbon formed on the surface of the metal particles. If desired, the carbonizing apparatus 10 may be directly heated by a furnace as shown in Fig. 4, in which case the processing operation may be the same as heretofore described, or it 35 may be conducted without passing hot oil vapors, gas or steam through the carbonizing bed 9, in which case I prefer to employ light oil vapors, gas, or steam to aid in removing the generated vapors from the carbonizing apparatus 10. Such 40 vapor, gas or steam may enter above the carbonizing bed to sweep away the vapors generated by the bed and released by the decomposable oil supplied through nozzles 29. The vapor, gas or steam above referred to may be supplied by pipes 45 not shown paralleling oil distributing pipes 28, said vapor, gas or steam being of sufficient temperature that it will not cause material condensation of generated vapors. While I have herein described carbonization with the use of vapor, 50 gas or other fluid, it is to be understood that while I prefer the use of such, its use is not absolutely essential to effect carbonization with the apparatus shown in Fig. 4. Further, while I prefer to operate the process in a substantially continuous 55 manner as heretofore described, it is within the scope of the invention to operate the process as a batch operation, in which case using the carbonizing apparatus shown, the element 56, would not be in use during carbonization, and the 60 blades 54 and shaft 55, would be rotated or oscillated to prevent consolidation of the carbonaceous masses, I may employ a carbonizing element 10, of simple cylindrical shape, the balance of the apparatus and the operation in each case being 65 substantially as heretofore described.

It is to be understood that carbonization may be conducted without substantial molecular alteration taking place in coil 7 or 52, the essential condition in such case being that the material heated 70 in these coils is of sufficient volume and attains sufficient temperature therein to accomplish the desired degree of vaporization and superheat necessary to perform the functions intended by its use in the process.

It is to be understood that heat and pressure measuring instruments will be used at all points in the unit where desirable. The unit will also be equipped with sampling devices where needed, also with safety pressure devices. In Figs. 2, 3 and 4, I have shown a method for cooling the various shafts employed in carbonizer 10, involving the construction of said shafts in hollow form through which a stream of cooling fluid is circulated. Lines containing valves 15, 16 and 65, are used only when starting or stopping operations, at which time these valves are manipulated to permit flow through the respective lines as indicated by arrows. It is to be understood that the process of this invention may be carried out as herein described when using heated fluids such as flue gases, hydrocarbon gases, including water gas, hydrocarbon vapors, inert gases, steam, etc., or mixtures thereof. The invention is not limited 10 in its application to the specific apparatuses shown, which are only of preferred form capable of carrying out the invention, the size, shape, material or arrangement of the apparatus employed being immaterial, so long as the results 15 obtained thereby are in accordance with the processing principles herein taught.

Having described my invention, what I claim is:

1. A process for the pyrolysis of hydrocarbons which comprises subjecting a limited quantity of solid carbonaceous matter substantially reducible to carbon by pyrolysis to a carbonizing temperature in a closed zone under disintegrative mechanical classification and producing carbon particles of restricted size, discharging said hydrocarbons on said particles maintained in said zone at the coking temperature of said hydrocarbons and producing cracked vapors while progressively depositing carbon on said particles, respectively releasing and withdrawing from said zone said vapors and accreted carbon particles exceeding said restricted size, dephlegmating and condensing out of the released vapors preferred fractions, and returning to the process less preferred fractions for pyrolysis as aforesaid.
2. A process for the pyrolysis of hydrocarbons which comprises subjecting a limited quantity of carbonaceous matter such as coal to a coking temperature in a closed zone under disintegrative mechanical classification and producing coke particles of restricted size, discharging said hydrocarbons on said particles maintained in said zone at said coking temperature and producing cracked vapors while progressively depositing carbon on said particles, respectively releasing and withdrawing from said zone said vapors and accreted carbon particles exceeding said restricted size, dephlegmating and condensing out of the released vapors preferred fractions, and returning to the process less preferred fractions for pyrolysis as aforesaid.
3. A process for the pyrolysis of relatively heavy hydrocarbons which comprises subjecting a limited quantity of coal to a coking temperature in a closed zone under disintegrative mechanical classification and producing coke particles of limited maximum and less size, discharging said hydrocarbons on said particles maintained in said zone at said coking temperature and producing cracked vapors while progressively depositing carbon on said particles, respectively releasing and withdrawing from said zone said vapors and accreted carbon particles exceeding said maximum size while effecting increscence of carbon particles of less size, dephlegmating and condensing out of the released vapors gasoline, and returning to the process non-gasoline fractions for pyrolysis as aforesaid.

ing out of the released vapors preferred fractions, and returning to the process less preferred fractions for pyrolysis as aforesaid.

4. A process for the pyrolysis of relatively heavy hydrocarbons which comprises discharging such hydrocarbons on carbon particles of limited maximum and less size disposed in a coking zone wherein said particles are mechanically agitated and classified at the coking temperature of said hydrocarbons, dissociating the latter into vapors and carbon, progressively depositing said carbon on said particles, respectively releasing and withdrawing from said zone said vapors and accreted carbon particles exceeding said maximum size while effecting increscence of carbon particles of less size, dephlegmating and condensing out of the released vapors preferred fractions, and returning to the process less preferred fractions for pyrolysis as aforesaid.

5. A process for the pyrolysis of petroleum hydrocarbons which comprises discharging such hydrocarbons on coke particles of limited maximum and less size disposed in a coking zone wherein said particles are mechanically agitated and classified at the coking temperature of said hydrocarbons, dissociating the latter into gasoline-containing vapors and carbon, progressively depositing said carbon on said particles, respectively releasing and withdrawing from said zone said vapors and accreted carbon particles exceeding said maximum size while effecting increscence of coke and carbon particles of less size, dephlegmating and condensing out of the released vapors gasoline, and returning to the process non-gasoline fractions for pyrolysis as aforesaid.

6. A process for the pyrolysis of petroleum hydrocarbons which comprises discharging such hydrocarbons on coke particles of limited maximum and less size disposed in a coking zone wherein said particles are maintained under mechanical agitation and classification at the coking temperature of said hydrocarbons through indirectly applied heat, dissociating said hydrocarbons into gasoline-containing vapors and carbon, progressively depositing said carbon on said particles, respectively releasing and withdrawing from said zone said vapors and carbon accreted particles exceeding said maximum size while effecting increscence of coke and carbon particles of less size, dephlegmating and condensing out of the released vapors gasoline, and returning to the process non-gasoline fractions for pyrolysis as aforesaid.

7. A process for the pyrolysis of petroleum hydrocarbons which comprises discharging such hydrocarbons on a limited quantity of coke particles of controlled maximum and less size disposed in a coking zone wherein said particles are maintained under mechanical agitation and classification at the coking temperature of said hydrocarbons through heat exteriorly applied to said zone, dissociating said hydrocarbons into gasoline-containing vapors and carbon, progressively depositing said carbon on said particles, respectively releasing and withdrawing from said zone said vapors and carbon accreted particles exceeding said maximum size while effecting increscence of coke and carbon particles of less size, dephlegmating and condensing out of the released vapors gasoline, and returning to the process non-gasoline fractions for pyrolysis as aforesaid.

8. A process for the pyrolysis of relatively heavy petroleum hydrocarbons which comprises discharging such hydrocarbons on a limited

quantity of coke particles of controlled maximum and less size disposed in a coking zone wherein said particles are maintained under mechanical agitation and classification at the coking temperature of said hydrocarbons through contact with heated hydrocarbon vapor, dissociating said hydrocarbons into gasoline-containing vapors and carbon, progressively depositing said carbon on said particles, respectively releasing and withdrawing from said zone hydrocarbon vapors and accreted carbon particles exceeding said maximum size while effecting increscence of coke and carbon particles of less size, dephlegmating and condensing out of the released hydrocarbon vapors gasoline, and returning to the process non-gasoline fractions for pyrolysis as aforesaid.

9. A process for the pyrolysis of relatively heavy petroleum hydrocarbons which comprises discharging such hydrocarbons on a limited quantity of coke particles of controlled maximum and less size disposed in a coking zone wherein said particles are maintained under mechanical agitation and classification at the coking temperature of said hydrocarbons through contact with a stream of heated hydrocarbon vapor substantially undecomposed at said coking temperature, dissociating said hydrocarbons into gasoline-containing vapors and carbon, progressively depositing said carbon on said particles, respectively releasing and withdrawing from said zone hydrocarbon vapors and accreted carbon particles exceeding said maximum size while effecting increscence of coke and carbon particles of less size, dephlegmating and condensing out of the released hydrocarbon vapors gasoline, and returning to the process non-gasoline fractions for pyrolysis as aforesaid.

10. A process for the pyrolysis of relatively heavy petroleum hydrocarbons which comprises discharging such hydrocarbons on a limited quantity of coke particles of controlled maximum and less size disposed in a coking zone wherein said particles are maintained under mechanical agitation and classification at the coking temperature of said hydrocarbons through heat exteriorly applied to said zone and contact with a stream of heated hydrocarbon vapor substantially undecomposed at said coking temperature, dissociating said hydrocarbons into gasoline-containing vapors and carbon, progressively depositing said carbon on said particles, respectively releasing and withdrawing from said zone hydrocarbon vapors and accreted carbon particles exceeding said maximum size while effecting increscence of coke and carbon particles of less size, dephlegmating and condensing out of the released hydrocarbon vapors gasoline, and returning to the process non-gasoline fractions from such dephlegmation for further conversion and production of residual fractions for pyrolysis as aforesaid.

11. A process for the pyrolysis of relatively heavy petroleum hydrocarbons which comprises the continuous steps of discharging such hydro-

carbons on coke particles of limited maximum and less size disposed in a coking zone wherein said particles are maintained under mechanical agitation and classification at the coking temperature of said hydrocarbons through contact with a stream of hydrocarbon vapor substantially undecomposed at said coking temperature, dissociating said hydrocarbons into vapors and carbon, progressively depositing said carbon on said particles and expelling from said zone said vapors by said stream of heated hydrocarbon vapor, withdrawing from said zone accreted carbon particles exceeding said maximum size while effecting increscence of coke and carbon particles of less size, dephlegmating and condensing out of the expelled hydrocarbon vapors preferred gasoline fractions, and returning to the process uncondensed hydrocarbon vapor and relatively heavy residual fractions resulting from such dephlegmation for pyrolysis as aforesaid.

12. A cyclic process for the pyrolysis of relatively heavy petroleum hydrocarbons into gasoline-containing light hydrocarbons and carbon which comprises converting said relatively heavy hydrocarbons into distillate and residual fractions, discharging said residual fractions on coke particles of limited maximum and less size disposed in a coking zone wherein said particles are maintained under mechanical agitation and classification at the coking temperature of said residual fractions by contact with a stream of hydrocarbon vapor derived from said distillate fractions and heated to the coking temperature of said residual fractions, dissociating said residual fractions into gasoline-containing vapors and carbon, progressively depositing said carbon on said particles and expelling from said zone said vapors by said stream of hydrocarbon vapor, withdrawing from said zone carbon accreted particles exceeding said maximum size while effecting increscence of coke and carbon particles of less size, dephlegmating and condensing out of the expelled hydrocarbon vapors gasoline, and returning to the process non-gasoline fractions from such dephlegmation for further conversion and production of residual fractions for pyrolysis as aforesaid.

13. A process for the pyrolysis of hydrocarbons which comprises subjecting a limited quantity of solid carbonaceous matter substantially reducible to carbon by pyrolysis to a carbonizing temperature in a closed zone under disintegrative mechanical classification and producing carbon particles of restricted size, discharging said hydrocarbons on said particles maintained in said zone at the coking temperature of said hydrocarbons and producing cracked vapors while progressively depositing carbon on said particles, respectively releasing and withdrawing from said zone said vapors and accreted carbon particles exceeding said restricted size, and condensing the released vapors.

JOSEPH F. DONNELLY.
